(57) CLAIM

What is claimed is the ornamental design for a basket, as shown and described.

DESCRIPTION

FIG. 1 is a perspective view of a basket showing a new design; FIG. 2 is a front view of the basket of FIG. 1; FIG. 3 is a side view of the basket of FIG. 1; FIG. 4 is a top view of the basket of FIG. 1; and, FIG. 5 is a bottom view of the basket of FIG. 1. The components of the display shown in broken lines illustrate portions of the basket form no part of the claimed design.
